UNITED STATES PATENT OFFICE.

CLYDE E. SWICK, OF SAN FRANCISCO, CALIFORNIA, ASSIGNEE TO HAWLEY PULP AND PAPER COMPANY, A CORPORATION OF OREGON.

MARKING DEVICE.

1,356,667.

Specification of Letters Patent. Patented Oct. 26, 1920.

Original application filed October 8, 1915, Serial No. 54,828. Divided and this application filed March 16, 1918. Serial No. 222,858.

To all whom it may concern:

Be it known that I, CLYDE E. SWICK, of San Francisco, in the county of San Francisco and in the State of California, have invented a certain new and useful Improvement in Marking Devices, and do hereby declare that the following is a full, clear, and exact description thereof.

The object of the invention is to provide a device which will mark a web of paper or similar material, to denote when portions of the web of predetermined lengths have passed such device.

Further objects and advantages of the invention will be apparent from the detailed description thereof contained hereinafter, in which I have described one embodiment of the invention, which is to be considered merely as illustrative of many other embodiments within the principle thereof. In the drawings:

Figure 1 is a side view of a portion of a machine containing a marking device made according to my invention;

Fig. 2 is a central section of such machine taken parallel with the plane of Fig. 1;

Fig. 3 is a view of the marking device shown detached, certain of its parts being in section, and

Fig. 4 is a section on line 4—4, Fig. 3, looking in the direction of the arrows.

Although the marking device may be used in connection with any desired machine for operating upon webs of paper or similar material, it is particularly adapted to be used in connection with a machine such as is disclosed in my co-pending application, Serial No. 54,828, filed October 8th, 1915, and entitled, "Paper interfolding machine," of which application the present case is a division.

In the drawings I have shown a portion of the frame of a machine, 1, which supports rolls 2 and 3 upon shafts 4 and 5 respectively. Gear 6 upon shaft 4 is driven from parts of the machine not shown, or in any other desired manner, and meshes with gear 7, which latter rotates the roll 3. These rolls are designed to perform any desired operations upon a web of paper or similar material, and will not be described in detail as their specific construction is not material to this invention.

The marking device is located in the path of the web before it reaches the rolls 2 and 3, and is intended to indicate upon the web when predetermined lengths of the same have been operated upon by the rolls. For this purpose the web A is fed into the machine between a printing bed roll 7¹ mounted upon a shaft 8, and a printing cylinder 9, which latter is mounted upon a shaft 10. The web then passes over a feeding roll 11 mounted upon a shaft 12, a tension roll 13 supported upon an arm 14, carried by a shaft 15, being provided to press the web against the surface of feeding roll 11. From this point the web passes to roll 2 where it is operated upon as above described.

The marking mechanism may conveniently be actuated by providing a gear 16 upon shaft 12 which meshes with gear 6, and which also meshes with a gear 17 upon a shaft 8 which carries the printing bed roll 7¹. A further gear 18 carried by shaft 10 transmits motion from shaft 8 to the shaft 10 which carries the printing cylinder 9.

In order to actuate the marker, later to be described, I have employed the following mechanism, the details of which, however, are not essential. Gear 17 is provided with a hunting tooth 19 which is secured preferably to the face of said gear by means of a screw 20 and a pin 21. The gear 18, on the other hand, is provided with a movable slide 22, having a projection 23 adapted to be engaged by tooth 19 hereinafter described. The slide 22 has furthermore a longitudinal slot 24 which receives one end of a lever 25, which lever is held in position upon shaft 10 by means of a clamp 26. The other end of the lever 25 rests beneath a marker 27 in a recess 28 in the printing cylinder 9, which marker 27 is normally held in retracted position by a spring 29. A plate 30, held in place by screws 31 may be provided to hold removably in place the marker 27 and spring 29. An inking roll 32 on an arm 33 is held in position to engage the marker 27 as it is rotated with printing cylinder 9.

In the operation of the device, gears 17 and 18 are of such selected ratio that projection 23 is engaged by tooth 19 whenever the desired length of the web has passed

over the bed roll 7. For instance, the gear 17 may be provided with seventy-four teeth, while the gear 18 is provided with seventy-five teeth, so that the teeth on gear 54 will gain one tooth during every revolution thereof, and tooth 19 will engage projection 23 once every seventy-five revolutions. Slide 22 and its projection 23 are normally pressed into outer position by spring 29, and the marker 27 is at the same time held in retracted position. When tooth 19 engages the projection 23, slide 22 is pushed thereby into its inner position, and lever 25 is tilted to advance marker 27 into a position to engage the web as the latter passes over bed roll 7¹. It will be apparent that by changing the ratio of gears 17 and 18, any desired lengths of the web may be periodically marked off in a similar manner.

20 While I have described my invention above in detail it is obvious that many changes may be made therein without departing from its spirit as defined in the appended claims.

25 I claim:

1. A marking device comprising a bed roll for receiving a web of material to be marked, a rotating printing cylinder adjacent thereto, a marker reciprocably mounted upon said cylinder and normally held in retracted position, intermeshing gears for rotating the bed roll and the printing cylinder, and co-operating members respectively carried by said gears periodically engaging to advance said marker into position to contact with the web.

2. A marking device comprising a printing bed roll for receiving a web of material to be marked, a printing cylinder and roll, 40 said cylinder and roll being mounted upon adjacent shafts, a marker reciprocably mounted upon said cylinder, means for rotating said shafts and a device carried by one of said means for periodically moving said marker into position to contact with the web.

3. A marking device comprising a bed roll for receiving a web of material to be marked, a marker, said roll and marker being mounted upon adjacent shafts, intermeshing gears on said shafts for driving the bed roll and the marker, and means on said

co-operating gears for moving said marker into position to contact with said web when a certain point on one gear engages a certain point on the other.

4. A marking device comprising a bed roll for receiving a web of material to be marked, a marker, said roll and marker being mounted upon adjacent shafts, intermeshing gears upon said shafts, a hunting tooth on one of said gears, and a cam device upon the other gear connected to said marker, and adapted to be actuated by said tooth to advance the marker into position to contact with the web.

5. A marking device comprising a bed roll for receiving a web of material to be marked, a shaft adjacent thereto, gears for driving said roll and shaft, and means carried by said driving gears for periodically marking the web as it passes over the roll.

6. A marking device comprising a bed roll adapted to receive a web of material to be marked, a shaft adjacent thereto, gears respectively for driving the roll and shaft, said roll gear having a tooth, a movable slide on the shaft gear adapted to be engaged by said tooth, and a marker actuated from said slide.

7. A marking device comprising a printing cylinder having a marker reciprocably mounted therein and normally held in retracted position, a slide reciprocably mounted adjacent such member, a lever engaging both said slide and marker, means for periodically moving said slide to actuate the lever and advance the marker, and means for passing a web of material over said printing cylinder.

8. A marking device comprising a printing cylinder having a marker reciprocably mounted therein, a spring normally holding the marker in retracted position, means for retaining the spring, a lever engaging said marker, means for periodically actuating the lever to advance the marker and means for passing a web of material over said printing cylinder.

In testimony that I claim the foregoing I have hereunto set my hand.

CLYDE E. SWICK.
